[57] CLAIM

The ornamental design for a child safety seat for vehicles, as shown and described.

DESCRIPTION

FIG. 1 is a front perspective view of a child safety seat for vehicles showing my design;

FIG. 2 is a side elevational view;

FIG. 3 is a front elevational view;

FIG. 4 is a top plan view;

FIG. 5 is a rear elevational view;

FIG. 6 is a bottom plan view; and

FIG. 7 is a front perspective view wherein the abdominal pad and strap system are shown in the disconnected position.

The side of the child safety seat not shown is a mirror image of the side shown in FIG. 3.
